VALUE-STAMPING MACHINE

Erich Komusin, Berlin, Germany, assignor, by
mesne assignments, to Johannes Paasch,
Magdeburg, Germany

Application June 17, 1929, Serial No. 371,453
In Germany October 14, 1924

13 Claims. (Cl. 235—101)

This invention relates to a value-stamping machine usable, for example, as a franking machine, with a removable prepayment key in which, after the sum to which the machine is set by the prepayment key, is exhausted, the machine becomes automatically locked against further use.

Machines are already known in which, for the purpose of an exact mutual control by the user and the authorities, the machine itself as well as the key for fixing the total amount, or prepayment key, are provided with a counting mechanism which continually registers the number of rotations of the key and, since each rotation of the key corresponds to a definite fixed amount, the particular total prepaid amount can be ascertained. The registering devices of this kind hitherto employed only allow of the registration of the number of equal prepaid amounts and not their actual sum, so that the final determination of the consumption of value marks always necessitates a calculation—i. e., a multiplication. Moreover, these registering devices can be used only in value-stamping machines which can only stamp continually equal values and for which the fixing of the total prepaid sum can only be carried out by means of a number of definite units.

In contradistinction to this, the subject matter of the invention is characterized by the feature that the fixing of the consumption limit, as well as the summation of the values determining it, is effected always in accordance with the actual amount, in an adding mechanism of the value-stamping machine itself as well as in the adding mechanism of the prepayment key; it being immaterial whether the gradual consumption of the prepaid amount is caused by stampings of larger or smaller values. The setting of the value-mark printing mechanism to a larger or smaller amount can, in fact, be altered as desired after each duly completed stamping, so that the limit of consumption is also determined not by the number of stampings but by the values stamped.

The machine is used as follows:—After being set to the prepaid amount, it is placed upon the article to be stamped—e. g. a letter or a card—and is moved forward by hand or mechanically when the drum shaped printing mechanism of the machine rolls on the article through the distance that is necessary for performing a complete stamping operation, whereupon it is locked against further movement. To perform a fresh stamping operation, the machine must first be lifted from the stamped article, whereupon it becomes ready for further use. After the prepaid amount is exhausted, the printing mecha-

nism drum is locked by a second locking device which liberates the printing mechanism drum only after the machine is set for a further prepaid amount.

The particular value for which the machine is set is printed by means of the drum-shaped printing mechanism as follows:—The number representing the value is located horizontally in its frame and in this way it is rendered possible for the number-printing wheels of the value-printing mechanism or mechanisms to be mounted on one or two shafts which are arranged in the proximity of the casing of the printing mechanism drum as chords to this casing. The printing of the figures of the value-printing wheels which are at the time being in the printing position, is effected as the result of this arrangement on rotation of the printing mechanism drum not simultaneously but successively in the direction of the rolling movement, so that the value figure is located, after a stamping operation, parallel to the upper and lower edges of the stamped surface—i. e., horizontally in its frame—and can consequently be easily read without error.

For altering the setting of the value-printing mechanism all the setting members (setting wheels or levers) of the setting device on the left-hand side of the value-stamping apparatus, are moved together from their ordinarily assumed locked position by means of a special setting member and then again returned together into the last mentioned position.

Various examples of the invention are represented by the accompanying drawings of which:

Fig. 1 is a side elevational view;

Fig. 2, is a top plan view;

Fig. 3 is a bottom plan view;

Fig. 4 is a rear elevational view, and

Fig. 5, is a front elevational view of a value-stamping machine, which may be used as a franking machine, for printing one or two-figure values.

Figs. 6 to 17a represent an example of a value-stamping machine for use in printing four-figure values, of these:

- Fig. 39 is a further detail thereof.
- Figs. 40 and 41 show different details of the example illustrated by Figs. 1 to 5:
- Fig. 40 shows a partial side view of the printing mechanism drum, and
- Fig. 41 is a corresponding under view partly in section;
- Fig. 42 shows a partially cut-away side view of the printing adding mechanism of the example;
- Fig. 43 is a corresponding plan partly broken away, and
- Fig. 44 is a plan of the operating drum;
- Figs. 45 to 48 show details of the printing adding mechanism.
- Figs. 1 to 5 are about $\frac{2}{3}$ of the actual size; Figs. 6 to 18 show the actual size; Figs. 18 to 33, 38 and 42 to 48 are on an enlarged scale; and Figs. 34 to 37, 40 and 41 show the actual size.

General

All the examples of the value-stamping machine have a box-like casing *a* which is closed on its left-hand side by a lid *c* secured by screws *b*. At its upper edge the lid *c* is provided with an attachment *d* hollowed out in the form of a spoon which serves for the insertion of the thumb of the right hand whilst to the right-hand side of the casing *a* there is secured an oblique bracket *e* beneath which the tips of the other four fingers can engage. On its under side the casing *a* has a recess *f* through which there protrudes externally a small portion of the printing mechanism drum *g*. Two slots formed at the rear end of the bottom of the casing have protruding through them running wheels *h* which facilitate the pushing forward of the value-stamping machine. The casing *a* is closed at the rear by a removable door *i* which is protected from unauthorized opening by a screw *j* secured by a leaden seal and a second leaden seal *k*. In the front of the casing *a* there is inserted an inking mechanism *l* which is formed as a separate unit which can, by pressing on a lock button *m*, be readily removed from the casing—for example, for the purpose of refilling it with ink.

The casing lid *c* bears on its outside the setting device *n* which can be used for setting the machine to the desired stamp value and is differently constructed for the several examples. In the case of the example for printing two-place values according to Figs. 1—5, 39 and 40, the setting device has two setting levers *o*1 and *o*2, the former of which serves for setting the machine for units and the second for setting it for tens. The setting of these setting levers can, however, be effected only if a locking lever *p* be pressed downwards. When setting has been effected, the locking lever *p* is again moved upwards and so locks the levers *o*1 and *o*2 in their new positions. The setting devices of the remaining examples will be described in detail hereinafter.

The interior arrangement of all the examples are substantially the same, except for differences specially emphasized or certain singly dealt with constructions.

The printing mechanism drum

Into the casing 1a (Figs. 6 and 11) of the value-stamping machine there is inserted (as seen from above) a rectangular supporting frame 2a which serves as a bearing for an axle 3a. A drum 75

shaped printing mechanism 4a (Figs. 6, 14 and 15) is rotatably mounted on the axle 3a. The surface of this drum shaped printing mechanism is provided with, for example, a set of printing devices, partly variable and partly permanent or invariable is provided on each half of the periphery of the drum, which protrudes from an aperture in the bottom of the casing 1a. On the drum being rolled on an article laid thereunder, for example a letter or postcard, an impression of one set of the printing devices will be printed on the article at each half revolution of the drum. The invariable printing devices serve, for example, for printing the name of the place, the post office mark, the apparatus number and certain trade inscriptions or figures, whilst the variable printing devices of each set consist of a value-printing mechanism 9a and a printing adding mechanism 10a which serves to sum up the individual amounts represented by the individual stampings and to print the sum continuously. The shaft 11a shown in Fig. 14 supports two printing adding mechanisms 10a, the shaft 11a being broken away and a single printing adding mechanism being illustrated. Each of the two adding mechanisms 10a is composed of a number of number-printing wheels 12a (Figs. 14 and 14a) which are rotatable on a shaft 11a connecting together the two drum ends 7a (Fig. 14a) and 8a (Fig. 14) so that the numbers to be printed, protrude outside the casing of the drum through a transverse slot in the casing. Of the number-printing wheels 12a of each adding mechanism 10a, the number printing wheel 12a, for example, of the highest number position, is connected with a hollow shaft 13a (Fig. 14a) which is pushed on the shaft 11a, passes through the righthand (in relation to the direction of working of the value-stamping machine) drum end 7a and carries on its free outer end two operating wheels 14a (Figs. 14, 14a and 15) each of which has five teeth. These are displaced in relation to each other in such a manner that the teeth of the one operating wheel lie opposite to the teeth gaps of the other operating wheel. With the particular double-operating wheel of these two pairs of operating wheels there co-operates, under conditions hereinafter to be explained, a somewhat larger counter-wheel 14'a, the shaft 16a of which (Figs. 6, 8, 9 and 15) is rotatable in the rear portion of the supporting frame 2a. A leaf spring 18a (Fig. 15) fixed to the rear transverse yoke 15a of the supporting frame 2a lays itself in the teeth gaps of the counter-wheel 14'a and acts like a brake so that the wheel 14'a ordinarily remains in its normal position. On a journal 21a, mounted in the bow-shaped upper end of the upwardly extending arm 19a (Figs. 14, 15, 6, 8 and 9) of the supporting frame 2a, there is rotatably mounted a double-armed lever 20a which a tension spring 22a constantly seeks to keep in the position shown in Fig. 15 but which, however, in opposition to the action of this spring normally assumes a position in which it engages with its hook-shaped end 23a the next tooth of the operating wheel 14'a. The oppositely forked end of the lever 20a serves for mounting a running wheel 24a which is rotatable about an axle 25a and on rotation of the printing mechanism drum 4a rolls on the edge 5a of the right-hand drum end 7a in which there are formed two flat edge recesses 119a (Fig. 15). As soon as the running wheel 24a falls into one or the other of the recesses 119a, the lever 20a can

assume the position shown in Fig. 15 and thus liberate the hitherto locked counter-wheel 14'a. As soon, however, as the printing mechanism drum 4a is rolled further on the particular article laid thereunder, the lever 20a, overcoming the resistance exerted by the spring 22a, swings out so that its hook-shaped end 23 engages with the next tooth of the counter-wheel 14'a and again renders its rotation impossible. The object of this arrangement will be explained hereinafter.

The prepayment setting

The shaft 16a (Figs. 8, 9 and 15) of the counter-wheel 14'a has in proximity to the middle thereof a toothed wheel 26a, which is in engagement with a toothed wheel 27a mounted at right angles thereto. The shaft 28a of this second toothed wheel 27a is rotatable in bearings 29a and 30a (Figs. 8 and 9) of the rear supporting frame yoke 15a and carries on its outer end a disc 31a, which is formed on the edge of its front left-hand surface (according to Figs. 6, 8 and 9) with ten notches 32a. On the free outer end there is pushed a setting knob 33a which is both rotatable and longitudinally displaceable on the shaft 28a but is normally pressed rearwardly—i. e., to the right according to Figs. 6, 8 and 9—by a compression spring 36a bearing against the disc 31a. This setting knob 33a is provided with a pointer 37a (Figs. 7 and 8), the hook-shaped end of which can, by the action of the compression spring 36a be brought to lie in one or other of the notches 32a in accordance with the setting of the knob 33a.

The setting knob 33a has on its rear surface an extension 34a in the form of a polygon which lies at a small distance behind an opening 71a (Figs. 11 and 6) formed in the locking flap 70a (Fig. 11) of the machine casing 1a and is accessible through this opening. The opening 71a is, however, advantageously normally kept locked by a slide, lid or the like which can be opened after the removal of any desired lock. The shaft 28a terminates in a round head 35a (Fig. 7) which rests in a corresponding bore in the setting knob 33a, 34a and is provided with a depression 35'a in the form of a polygon.

Between the bearings 29a (Figs. 8 and 9) and the notched disc 31a there is provided a second notched disc 38a which agrees in shape and size with the notched disc 31a but is, however, freely rotatable about the shaft 28a; its notches 40a face the notched disc 31a and it is rigidly connected with a toothed wheel 41a on the side opposite to the notched side. This notched wheel 41a serves, in the manner hereinafter explained, for driving the so-called main adding mechanism 43a (Figs. 6 to 9) which is arranged parallel to the shaft 16a on an axle 47a mounted in shoulders 45a and 46a of the supporting frame yoke 15a. The driving of the main adding mechanism 43a is effected by a toothed wheel 48a which is fixed on the axle 47a and which, through the medium of an intermediate toothed wheel 49a, is set from the toothed wheel 41a of the notched disc 38a. The intermediate toothed wheel 49a rotates about an axle 50a (Figs. 7 and 9) of the bearing 29a carried by the supporting frame yoke 15a.

Opposite to the main adding mechanism is the prepaid amount or prepayment indicating device which consists of a roller 55a (Figs. 7 and 9) rigidly fixed to the counting mechanism axle 47a. This roller 55a bears on its surface the

- numbers "100", "200", and so on up to "1000" for example, and is rigidly connected, on the face which is turned away from the main adding mechanism 43a, with a locking cog-wheel 125a which possesses two teeth 126a for each number borne by the roller 55a. One or more than two teeth may be provided for each number borne by the roller 55a. The essential point is that the number of the teeth 126a, is divisible by 5
- 10 the number of numbers borne by the roller 55a. With the locking cog-wheel 125a there cooperates a flat locking rod 121a, which is normally pressed into the teeth gaps of the locking cog-wheel 125a by a compression spring 124a 11
- 15 acting on a pin 122a of the locking rod 121a. The locking rod 121a passes through a slot in the outer supporting frame shoulder 46a and the casing 1a and is provided on its outer end with a knob 123a by means of which it can when 16
- 20 necessary be pulled back so as to liberate the locking cog-wheel 125a. As soon as this takes place, a spiral spring 56a, which is fixed by one end to the counting mechanism axle 47a and by the other to the inner bearing 48a, automatically returns the prepayment indicating device 55a into its zero position after it (the spring 56a) has previously been more or less stressed 25 on the setting of the prepayment indicating device. 26
- 30 In contradistinction to the prepayment indicating device which is rotatable in both directions, the main adding mechanism 43a can only be operated in one direction, so that the amount added thereby can only continue to be increased. 31
- 35 In order to prevent the main adding mechanism from being operated further with the fraudulent intention of reaching its maximum capacity and re-setting it to zero and then setting it to a new lower amount, the highest place unit wheel 43'a 32
- 40 (Fig. 9a) is rigidly connected with a locking disc 44a, the ten notches 44'a of which can co-operate with a bell-crank locking lever 51a. This lever is 41
- 45 rotatably mounted on the casing of the main adding mechanism 43a or on an extension of or attachment to the supporting frame 2a and is so 46
- 50 acted upon by a spring 52a that it is continually pressed, with its locking catch 54a, through a recess 42a (Fig. 15) of the casing and against the locking disc 44a. By pressing on the knob-shaped end 53a (Figs. 9 and 9a) of the locking lever 51a, its locking catch 54a can be withdrawn 51
- 55 from the particular notch 44'a of the locking disc 44a occupied thereby, this, however, can only be done by the official who is provided with an unlocking device for the locking flap 70a (Fig. 11). 52
- The particular setting both of the main adding mechanism 43a and of the prepayment indicating device 55a can be read off through a window 57a or 58a (Figs. 11 and 6) provided in the casing 1a. 53
- 60 The setting of both counting mechanisms is effected by means of a setting key 59a (Figs. 10, 10a and 10b) which is itself constructed as the control counting mechanism and is to this end furnished in its hollow interior with an adding mechanism that is known per se. The figure wheels of this adding mechanism are rotatable on an axle 60a the free end of which is straight-edged or square shaped and fits exactly into the depression 35'a (Fig. 7) of the head 35a forming 61
- 65 the end of the shaft 28a (Figs. 7 to 9). The front end of the setting key 59a is in the form of a clutch 62a (Figs. 10 and 10a) by means of which it can be stuck on the polygonal extension 34a (Figs. 7 to 9) of the setting knob 33a, the straight 66
- 70 edged or square shaped axle end 61a (Fig. 10) 71
- 75 being at the same time pushed home into the depression 35'a. Like the main adding mechanism 43a, the control counting mechanism of the setting key 59a is also provided with a locking device, which prevents any attempted further operation of its highest place figure wheel 59'a. This figure wheel 59'a (Fig. 10b) of the key adding mechanism is to this end firmly connected with a locking disc 65a, the notches 66a of which co-operate with a spring-controlled locking rod 67a movable in the end wall of the key casing. Access to this locking rod is ordinarily cut off by a head 63a which is suitably detachably fixed on the rear end of the setting key 59a and serves as a mount for the compression spring 68a that acts upon the locking rod 67a. The particular setting of the key adding mechanism, that can be operated in only one direction, may be read off through a lateral window 64a of the setting key. 20
- The locking device for the printing mechanism drum*
- The printing mechanism drum 4a (Figs. 6 and 14) is provided on its left end wall 8a (in relation to the direction of operation of the value-stamping machine) with stop pins 8'a the number of which corresponds to the number of sets of printing devices that are provided at the wall of the printing mechanism drum since in the example 30 represented the printing mechanism drum carries two sets of printing devices, two stop pins 8'a are accordingly fixed to the drum end 8a. These stop pins 8'a serve for limiting the rolling movement of the printing mechanism drum 4a in such a manner that at any time only one set of the printing devices arrives in the printing position. To this end the following arrangement is provided: In an extension 74a (Figs. 6, 12 and 13) of the supporting frame 2a there is fixed a shaft 76a on which a bell-crank lever 79a, 80a is mounted so as to be rotatable in the space between the supporting frame 2a and the left-hand drum end 8a. A tension spring 75a constantly tends to press the arms of this bell-crank lever downwards. The lower arm 80a of the bell-crank lever 79a, 80a has its end portion 77a formed like a sledge runner and the end of its upper arm 79a is in the form of a laterally bent out locking catch 78a which can under the action of the tension spring 75a be caused to enter alternately two edge recesses 6a of the drum end 8a. On the arm 80a of the bell-crank lever 79a, 80a there is rotatably mounted a small locking lever 81a (Figs. 12, 12a and 12b) which can co-operate by means of a tappet 81'a with the corresponding nose 86a on a second locking lever 85a. The locking lever 81a is rotatable about a shaft 81'a mounted on the arm 80a and is acted upon by a tension spring 83a which constantly tends to move it upwards—i. e., in the clockwise direction. This rotation is, however limited by a shorter arm 84a of the locking lever 81a encountering a stop pin 82a of the arm 80a. The locking lever 85a is rotatable about a shaft 85'a which is carried by the bow-shaped end of a downward extension 88a (Figs. 6, 12, 12a, 12b and 13) of the supporting frame 2a. The locking lever 85a is also normally drawn upwards by a tension spring 87a until its double-edged stop nose 86a comes to lie against a stop pin 88'a (Figs. 12 and 12a) of the frame extension 88a. 40
- The sledge-runner shaped arm 80a of the bell-crank lever 79a, 80a carries further an upwardly extending locking arm 89a (Figs. 6, 12 and 12a) 75

which when the arm 80a is raised, engages with its free end in the slot-shaped recess 91a of a hub 92a and thus prevents a rotation of the bushing 92a, which is rigidly connected with the hub 92a and rotatable on the drum axle 3a, as well as of the setting segments 90a (Fig. 6). The object of this arrangement is to render impossible a shifting, during the printing operation proper, of the value-printing mechanism 9a 10 (Fig. 14) that is adapted to be set by the setting segments 90a.

For the purpose of preventing a rotation of the printing mechanism drum 4a (Figs. 6, 14 and 15), and consequently, the use of the value-stamping 15 machine, after the prepaid amount has been used up, there is rotatably mounted, on a shaft 116a (Fig. 6) on the rear portion 2a, a bell-crank lever 116a, 118a, which is adapted to come to lie with its downwardly extending arm 118a in front 20 of one or the other of two locking catches 117a fixed to the left-hand drum end 8a, but which is thrown back by a spring not shown into its position of rest (Fig. 6) in which the catches 117a can travel unhindered past the arm 118a.

25 The inking device

The inking of the particular printing devices at any time being printed with is effected, directly before making each fresh impression, by 30 an inking device which is removably attached by means of a plate 97a (Fig. 6) to the inside of the front wall of the casing 1a and continually co-operates through the medium of an inking roller 94a (Figs. 6, 16 and 17) with the printing devices 35 of the printing mechanism drum 4a. The inking roller 94a is carried by two supporting arms 95a which are rotatable about an axle 95a mounted in bearings of the plate 97a and are each continually pressed upwards by a compression spring 40 96a. The upper portion of the inking device consists of a box-shaped ink reservoir 98a that is provided with a closable filling opening 100a and a cap 101a which has an opening for the purpose of admitting air. In two lateral upwardly extending 45 supporting arms 103a of the ink reservoir 98a there is rotatably mounted a shaft 102a, on one end of which there is fixed a pivoted arm 107a (Figs. 6, 16 and 17) which lies in the plane of the drum pins 8a (Figs. 6 and 14) and is adapted 50 to be adjusted and fixed in position, whilst it (the shaft 102a) carries on its middle portion an arm 104a. On the free end of this arm 104a there is pivoted a valve rod 105a which passes through a hole in the upper wall of the ink reservoir 98a 55 and with its conical end 106a normally closes the discharge opening 108a of the ink reservoir 98a. The discharge opening 108a opens into the ink trough 109a which is likewise rotatable by means of arm-like extensions 109a of its side 60 walls about the axle 95a and is provided on its under side with slots extending through its whole width. In the ink trough 109a which is closed by a lid 112a provided with an opening there is arranged beneath the discharge opening 65 108a a spreading rib 111a (Fig. 17a) which uniformly spreads the ink dropping thereon over the bottom of the ink trough by means of grooves therein. Finally, a ledge 113a (Figs. 17 and 17a) is also rotatable about the axle 95a by 70 means of lateral supporting arms and is caused, by the tension of two tension springs 114a to lie permanently with its under side upon the inking roller 94a; this ledge 113a serves to rub the ink flowing from the ink trough slots 110a uniformly over the whole width of the inking roller 75

94a. The tension springs 114a are suspended by their ends on pins 99a on the ink trough 109a and the rubbing ledge 113a, embrace the supporting arms 95a of the ink roller 94a as shown in Fig. 6 and consequently continually pull both the under side of the ink trough 109a and the rubbing ledge 113a against the inking roller 94a.

10 The method of using the machine, and its mode of operation

The machine is to be used in the following manner:—

The values or control marks, which can be printed, on letters or cards by means of both value-printing mechanisms 9a (Fig. 14) provided 15 in the printing mechanism drum, each represent, according to the value units associated with their respective figures, single values the consumption of which up to a definite limit—i. e., the prepaid amount—is to be checked and also finally 20 limited. The continuous checking of the consumption of value marks is effected by the printing adding mechanism 10a after the prepaid amount indication—i. e., the permissible limit of consumption of value marks—has previously, 25 on setting the machine, been placed so as to be visible in the prepayment indicating device 55a. At the same time as this placing of the prepayment indication according to its numerical value is effected, the control counting mechanism of 30 the setting key 59a is also operated according to the value amounts up to the limit and summed up thereby. The limiting of the permissible stamp consumption or franking is effected by a locking device consisting of the operating 35 wheels 14a and 14a (Fig. 15), the locking lever 20a, the two notch discs 31a and 38a (Figs. 6 to 9), the setting device 33a, 37a and the bell-crank lever 116a, 118a, whilst the main adding mechanism 43a, the prepayment indicating device 55a 40 and the control counting mechanism of the setting key 59a (Fig. 10) serve for taking up the number corresponding to the prepayment amount which is adjusted in each instance.

As already mentioned, the represented example of value-stamping machine can be used as a postage franking machine which may be left by the postal authorities with firms and private persons for the purpose of franking their postal communications. In this case, the user must prepay to the postal authorities the total amount that he calculates will cover the consumption of value marks over a certain period whereupon the postal authorities will limit the amount of use of the machine by a corresponding adjustment. This is effected in the following manner:— The supervising official inserts the setting key 59a (Fig. 10) with its clutch-like front portion 62a through the opening 71a (Figs. 11 and 6) of the locking flap 70a and on the polygonal extension 34a (Figs. 7 and 9) of the setting knob 33a, the front straight-edged end 61a (Figs. 10 and 10a) of the key adding mechanism 60a passing at the same time into the corresponding depression 35a (Fig. 7) of the head 35a which forms the outer end of the shaft 28a (Figs. 7 and 9). It is evident that the arrangement could be such that the locking flap 70a (Fig. 11) would possess no opening for the insertion of the setting key 59a but would for this purpose have to be itself unlocked and raised when necessary. After the setting key 59a has been inserted on the polygonal extension 34a, the key and the setting knob 33a (Fig. 9) are first depressed against 75

the resistance offered by the compression spring, when the hook-shaped end of the setting knob pointer 37a passes out of the particular notch 32a of the disc 31a occupied thereby and into 5 the opposite notch 40a of the disc 38a. If the setting key 59a is now turned in the clockwise direction, the disc 38a must, in consequence of the coupling of the setting key with the setting knob 33a, 34a and in consequence of the engagement 10 of the setting knob pointer 37a in one of the notches 40a, also take part in the rotation of the setting key and transmit it by means of its toothed wheel 41a and the intermediate toothed wheel 49a (Figs. 6 and 9) to the toothed wheel 15 48a. The toothed wheel 48a drives in the known manner by means of the axle 47a the figure wheel of the lowest order of the main adding mechanism 43a and moves it, and if desired the figure wheels of higher order by tens-operating gear- 20 ing, through the number units set at the time being on the notched disc 38a. Likewise, the fixed amount is transmitted by the axle 47a to the prepayment indicating device 55a previously set to zero. In the case of the example of the 25 invention represented by the drawings, the number units "1" to "10" of the two notched discs 31a and 38a correspond according to value to the figures provided on the highest place figure wheels 12'a (Figs. 14 and 14a) of each of the 30 printing adding mechanisms 10a. If these figures represent for example the hundreds units of the amount summed up by the printing adding mechanism 10a, the same is the case with the number units of the two notched discs 31a 35 and 38a—i. e., on setting the notched disc 31a there will be transmitted both into the prepayment indicating device 55a and to the figure discs of the lowest order of the main adding mechanism only hundreds units—e. g., hundred dollar amounts. Since on each such operation the locking rod 121a co-operating with the locking toothed wheel snaps in behind another tooth 126a, the prepayment indicating device 55a always takes up a position corresponding to the 40 particular amount paid and shows this amount in the window 58a (Fig. 11) of the casing 1a. The main adding mechanism 43a (Figs. 6 to 9) is constructed as a so-called stroke-counter—i. e., it is operated only in the additive sense 45 and thus always indicates the number limits up to which the value-stamping machine can print value or check marks, taking into account all earlier payments. The prepayment device 55a can, however, be operated both in an additive 50 sense and in a subtractive sense. When the prepayment indicating device 55a is operated in the additive sense, the main additive mechanism 43a is caused positively to take part in this operation by the common axle 47a, whilst on the subtractive 55 operation of the prepayment indicating device 55a, the setting at the time being of the main adding mechanism 43a remains unchanged in consequence of its construction as stroke- 60 counter. The subtractive operation of the prepayment indicating device 55a is automatically effected, as already stated, after the withdrawal of the locking rod 121a, by the spiral spring 56a which returns it into the zero position, where- 65 by the last paid in amount is cancelled for the purpose of enabling the machine to be set to a newly paid in amount. On setting the machine to the newly paid in amount, the operations hereinbefore described are repeated.

70 The operation of the control counting mecha-

nism arranged in the setting key 59a (Fig. 10) is effected as follows:—

When the value-stamping machine is in the condition of rest, the locking lever wheel 24a (Fig. 15) lies on the unbroken part of the drum edge and in this way forces the locking lever 20a to engage with its hook-shaped end 23a one of the teeth of the counter-wheel 14'a and thus to lock the latter against rotation. Consequently, the shaft 16a (Figs. 6, 8 and 9) of the counter-wheel 10 14'a and the toothed wheel 26a fixed to the said shaft 16a, as well as the toothed wheel 27a and its shaft 28a, are prevented from rotating. Since, on inserting the setting key 59a on the extension 34a of the setting knob 33a, the counting 15 mechanism axle 60a (Fig. 10) of the setting key is rigidly coupled with the shaft 28a by its engagement in the depression 35'a (Fig. 17 in the shaft head 35a, the axle 60a (Fig. 10) cannot, on the setting of the machine to the new pre-paid amount by the corresponding rotation of the setting key, take part in the rotational movement of the setting key but remains at rest together with the shaft 28a (Figs. 7 to 9). The result of the rotation of the setting key 59a (Fig. 20 25 10) in relation to its fixed axle 60a is that the control counting mechanism arranged in the setting key is operated simultaneously and to the same extent as the main adding mechanism 43a of the value-stamping machine that is station- 30 arily mounted and is driven by the rotation of the counting mechanism axle 47a (Figs. 8 and 9). The numbers that are visible in the window 64a (Fig. 10) of the setting key 59a and in the window 57a (Fig. 11) of the casing 1a represent 35 the total amount received or paid for which each apparatus has been set. Fraudulent shifting of the main adding mechanism 43a as well as of the control counting mechanism ar- 40 ranged in the setting key 59a is, as already ex- 45 plained above, prevented by the locking devices shown in Figs. 9a and 10b respectively which allow the further movement of the high place figure wheel of each of the two adding mechanisms in each case only after the removal of a specially secured lock and after a temporary withdrawal of the locking members 51a, 54a or 67a. Naturally, both adding mechanisms may 50 be fitted with a zeroizing device of a known kind for the purpose of enabling the machine to be reset to zero when necessary—e. g., when the value-stamping machine is given over to a new user.

After the setting of the machine to a new pre-paid amount is completed, the setting key 59a is withdrawn from the setting knob 33a, 34a (Figs. 7 to 9) and the coupling between the shaft 28a and the axle 60a, 61a (Fig. 10) of the setting key is thus discontinued. The setting knob 33a, 34a is immediately returned by the action 60 of the compression spring 36a (Figs. 8 and 9) into its position of rest with the result that the hook-shaped end of the setting knob pointer 37a leaves the notch 40a of the disc 38a up to then occupied thereby and is placed in the exactly opposite notch 32a of the disc 31a. The notched disc 38a, up to then taken with the setting knob pointer 37a, has in the meantime been locked against rotating backwards since it is integrally connected by the toothed gearing 41a, 49a, 48a as well as the shaft 47a with the prepayment indicating device 55a, which is secured against unintentional backward rotation by the locking rod 121a. Finally, the lid opening 71a (Fig. 11) 65 is locked and the lock secured.

The value-stamping machine prepared in this way can now be used by its user up to the fixed limit—i. e., until the exhaustion of the prepaid amount—for franking articles to be posted or 5 for whatever other purpose for which the machine is intended. If the user places the machine on the surface to be stamped—e. g., a letter—the sledge-like runners 77a (Figs. 6, 12, 12a 12b) which protrude somewhat from the casing 1a, are pushed in by the weight of the machine, when the bell-crank lever 79a, 80a turns about its shaft 76a so that the locking catch 78a formed on the upper arm 79a of the bell-crank lever leaves the edge recess 6a of the printing mechanism drum 4a till then occupied thereby. The drum 4a can thus now, on moving the machine forward, roll on the surface to be stamped. During the swinging of the bell crank lever 79a, 80a around its pivot pin 76a the locking lever 81a 10 mounted on the arm 80a comes into the path of a pin 81a mounted on the bottom 8a of the drum (see Fig. 14), so that this pin, during the further rotation of the drum, that is during the rolling on the surface to be stamped, gradually swings 15 the locking lever 81a downwards out of the position shown in Fig. 12a into that shown in Fig. 12b in the manner hereinafter described and for the purpose hereinafter set forth. By the raising of the bell-crank lever arm 79a, 80a, the 20 locking arm 89a has at the same time also been raised and pushed into the hub recesses 91a (Fig. 12) of the setting segments 90a (Fig. 6) so that both value-printing mechanisms 9a (Fig. 14) are secured against any shifting during the 25 next ensuing operation.

On pushing the machine forward by hand or mechanically, the printing drum 4a (Figs. 6, 13, 14 and 15) rolls every time through an angle of 180° on the surface to be stamped and in this 30 way effects the printing with the particular set of the printing devices that comes into question which are distributed over the cylindrical surface of the drum. Within a definite portion of the period of rotation of the drum, one of the 35 stop pins 81a provided on the left-hand drum end 8a approaches the locking lever 81a (Figs. 12, 12a and 12b) and slides along it and in so doing turns it downwards about its shaft 81'a until the tappet 81'a of this locking lever 40 counters the upper edge of the stop nose 86a of the second locking lever 85a. Yielding by the locking lever 85a under the action of the pressure exerted thereon by the tappet 81'a is impossible because the lower edge of the stop nose 45 86a abuts against the shaft 88'a and further the stop pin 81'a of the printing mechanism drum 4a has in the meantime encountered the second locking lever 85a. The stop pins 81'a and consequently also the printing mechanism drum 4a 50 itself are thus in common stopped from rotating by both locking levers 81a and 85a—so that, the printing mechanism drum is unable to roll any further. This interruption of the rolling movement takes place just after all the printing 55 devices pertaining to one set have completed their printing operation and one of the two edge recesses 6a (Fig. 6) of the left-hand drum end 8a again comes beneath the locking catch 78a of the upper bell crank lever arm 79a.

60 The further use of the machine is only rendered possible by lifting it from the stamped surface after the printing mechanism drum has become locked. The bell-crank lever 79a, 80a (Figs. 6 and 12) is then returned into its position of rest 65 (Fig. 6) by the pressure of the spring 75a, engages with its locking catch 78a in the edge recess 6a of the drum end 8a lying directly beneath it and at the same time returns the locking lever 81a (Fig. 12) mounted on the arms 80a from the position last occupied thereby (Fig. 12b) into the position shown in Fig. 12a. On its return movement the lever 81a is again freed from the pin 81'a that has up to then been resting on it, so that it can be pulled back into its position of rest (Fig. 12) by the pull of its spring 83a. At the 10 same time its tappet 81'a has also again liberated the stop nose 86a of the second locking lever, so that the latter no longer offers any resistance to further movement of the stop pin 81'a. Consequently, if the value-stamping machine is now 15 placed upon another surface to be printed and is moved forward, the printing mechanism drum 4a resumes its interrupted rolling movement, when the locking lever 85a is returned into its initial position by its spring 87a after being liberated by 20 the stop pin 81'a, whereupon the above described operations are repeated. The stop pins 81'a in conjunction with the locking lever 81a, 85a, thus produce the result that the rolling movement of the printing mechanism drum always remains limited 25 to a definite portion of its circumference—i. e., it takes place for as long as is necessary to bring about a printing operation by a set of mutually pertinent variable and invariable printing devices. After the due completion of this partial 30 rolling movement of the printing mechanism drum and its automatically ensuing locking, the locking levers 81a and 85a provided for this purpose are again rendered inoperative by simply lifting the machine. If, however, the machine is 35 raised before the completion of the partial rolling of the printing mechanism drum that is necessary for enabling printing to be effected by a complete 40 set of the printing devices, all the parts are maintained in the position in which they happen to be at the moment, since the locking catch 78a of the bell-crank lever 79a, 80a is then resting on the unbroken edge 5a of the drum end 8a and a return of the bell-crank lever and of the locking lever 81a mounted thereon into their position of 45 rest is therefore impossible. The interrupted stamping must consequently first be completed. Further, on placing the machine on the surface to be printed, any shifting of the value-printing mechanism 9a (Fig. 14) is, as already explained, 50 prevented by the operation of the locking arm 89a (Figs. 6 and 12) until the rolling movement of the printing mechanism drum that is necessary for duly performing a stamping operation has been completed, whilst on any interrupted stamping 55 operation the locking of the value-printing mechanism 9a is continued since in this case the bell-crank lever 79a, 80a which carries the locking arm 89a does not change its position.

60 The figure-printing wheels 12a (Figs. 14 and 14a) of the printing adding mechanism 10a are moved on, as already stated, on each stamping operation by the particular amount to which the value-printers 9a are set. The possibility of printing value marks with the aid of both value-printers 9a is limited by the size of the prepaid amount indicated by the prepayment indicating device 55a (Figs. 7 and 9) and summed up by the main adding mechanism 43a (Figs. 7 to 9) as well as by the control counting mechanism of the setting key 59a (Fig. 10). If this amounts, for example, to \$800, the machine is no longer usable as soon as the sum of the individual amounts expended by the stamping operations performed and 70 summed up by the adding mechanism 10a (Fig. 75

14) has reached \$800. In this case, this limitation of the printing of value marks is brought about in the following manner: Every time that in the course of the stamping operations the consumption of value marks reaches \$100, the value-printing wheels 12¹a (Figs. 14 and 14a) of each of the adding mechanisms 10a which register the hundreds units are moved forward one figure.

Naturally, if desired, any other value printing wheel could be connected with a hollow shaft for the purpose of thus enabling it also to be arranged that the corresponding number unit may act as a locking limit. In consequence of the rigid connection, effected by the hollow shaft 13a, between the value-printing wheel 12a and the double-operating wheel 14a, the latter also is in this case turned forward a tens division, so that instead of the tooth up to then employed, a new tooth of this double-operating wheel 14a, but lying on another plane, is led into the path of the counter-wheel 14¹a (Fig. 15). Each onward movement of the printing adding mechanism 10a and consequently of the double operating wheel 14a is effected, in a manner that need not be gone into here shortly before the locking catch 78a (Figs. 6 and 12) enters one of the two edge recesses 6a of the printing mechanism drum and the latter is stopped when one of its stop pins 8¹a encounters the locking levers 81a and 85a. Directly before this takes place, the tooth of the operating wheel 14a (Fig. 15), that has last been moved into the operating position, encounters the tooth of the counter-wheel 14¹a lying in its path and moves the counter-wheel forward a tens division. By means of the shaft 16a (Figs. 6 to 9) of the counter-wheel 14¹a the rotation of the latter is transmitted first to the toothed wheel 26a, then to the toothed wheel 27a engaging with the toothed wheel 26a and so finally by means of the shaft 28a to the notched disc 31a, so that the latter also is each time moved forward a unit. The rotation of the notched disc 31a takes place in this case, referring to Fig. 11, in the anti-clockwise direction. The step-by-step operation of the counter-wheel 14a and of the notched disc 31a is repeated as many times as number units—for example, hundreds—have been paid for—thus in the case chosen as example, 8 times. On the last (eighth) operation, the pointer 37a that naturally travels with the notched disc 31a strikes at the point indicated by "0" in Fig. 11, the lever arm 116a (Fig. 6) of the bell-crank lever 116a, 118a and swings it out in such a manner that its locking arm 118a is led into the path of both locking catches 117 of the drum end 8a and consequently makes the rolling of the printing mechanism drum 4a impossible. The machine is therefore locked against unlawful use until its next setting. On the next setting—for example, to a prepaid amount of \$500—the pointer 37a is removed through a corresponding distance—in this case 5 units—from the lever arm 116a and is placed in another notch 32a of the disc 31a, so that the bell-crank lever 116a, 118a liberated in this way can again be returned into its position of rest (Fig. 6) by its spring 115a. The machine is consequently now freed for further use.

As already stated above, the counter-wheel 14¹a is normally locked by the locking lever 20a, 23a (Fig. 15) and is always liberated only at the instant at which the step-by-step movement of the counter-wheel 14¹a and of the notched disc 31a integrally coupled therewith should be ef-

fected to the extent of one hundreds unit. The arrangement of the already mentioned edge recesses 119a for the running roller 25a of the locking lever 20a, 23a is consequently such that, at the moment when the operating wheel movement is effected, the running roller 25a is just passing through one of these recesses 119a and the locking lever 20a, 23a consequently liberates the counter-wheel 14¹a. When the operating wheel movement is completed the counter-wheel 14¹a is again locked by the lever 20a, 23a.

The device for operating the printing adding mechanism or mechanisms of the examples according to Figs. 18-39.

The printing mechanism drum 1 (Figs. 18, 20, 36 and 38) is advantageously provided with two value-printing mechanisms 30, arranged at 180° from each other, as well as with two addition printing mechanisms 23 which occupy, in relation to the pertinent value-printing mechanism 30, the position shown in Fig. 38. In the remaining figures, for the sake of simplicity and clearness, only a single value-printing mechanism and the pertinent addition-printing mechanism opposite thereto are represented.

The printing mechanism drum 1 is rotatable about an axle 2 (Figs. 18, 20, 22, 24, 25, 34) rigidly mounted in the frame of the roller stamp, on which axle a drum-shaped casing 4 of the kind hereinbefore described is rigidly fixed by means of a screw 5 (Figs. 18, 20) or the like. The shell of the toothed chain casing 4 is provided with a number of longitudinal slots 4', through which the teeth of toothed control chains 6 (Figs. 18, 20, 31, 33) or toothed segments 8 (Fig. 22), as the case may be, project. Each toothed control chain 6 serves for driving one of the control wheels 24' (Figs. 18, 20, 38), which effect the adjustment of the printing wheels 23 of the printing mechanism for the summation. The toothed control chains 6 are constructed as shown in Fig. 33—i. e., they are composed of individual angle members 6'', one limb a', b' of which is rotatably connected by a pin c' with the adjacent member 6''. The forked limb a', b' of the first chain member 6'' is rotatably fixed on a pin d rigidly mounted in the interior of the casing 4 (Fig. 31) whilst the opposite end of each toothed chain 6 is free. A cam disc 7 co-operates with each of these toothed chains 6, which are normally not tensioned in consequence of the aforementioned arrangement, the periphery of the said cam disc being formed with two steps of different heights. In the lower step 7'' lies along its whole length below the corresponding toothed chain 6, the latter will be unloaded and its teeth 6' will project through the slot 4' (Fig. 18) provided for them in the casing 4 towards the exterior. If, however, in consequence of a counterclockwise movement (Fig. 31) of the said cam disc 7, its higher peripheral step is brought below the toothed chain 6, this latter will have all its links pressed with the widened ends of its forked limbs a', b' (Fig. 33) against the internal surface of the shell of the casing and will thereby be tensioned in a position dependent upon the rotation of the cam disc 7 in such manner, that a corresponding number of its teeth 6' will pass through the slot 4' and will remain immovably in this position. The toothed chain can now act as a control member, although only when the control teeth 6' have already been secured in the working position by the action of the higher step of the cam disc, whilst the teeth of the chain links 6'' lying on the lower step 7'' of the cam disc cannot effect any controlling

operations in consequence of the lack of resistance. The cam discs 7 are provided with recesses 7', which co-operate with stop pins (not shown) provided on the casing 4 in such manner, that the toothed chains 6 never entirely lose their co-operation with the cam disc 7, inasmuch as, in this latter event the proper guidance of the teeth 6' in the slots 4' would be endangered. The cam discs 7 are fixed on hollow shafts 11, 11', 11'', 11''' (Figs. 20, 24, 32) which are arranged telescopically on the axle 2 and are provided at their free ends with a projecting tongue 21. The tongues 21 are, as is shown in Fig. 20, of different lengths, whilst the free ends of the hollow shafts 11, 11', 11'', 11''' lie in one plane.

Each of the toothed segments 8 (Figs. 18, 20 and 22) is mounted so as to be freely rotatable on the right hand side of the cam disc of the corresponding toothed chain 6 (considered with respect to Figs. 18 and 20) on the corresponding hollow shaft 11, 11', 11'' and 11''' respectively, by means of disc 10 (Fig. 22). The free end of a curved spring 12 engages a pin 9 provided on each disc 10, the said spring being attached on its other end to the casing 4 and tending to set the toothed segments continuously in motion in a clockwise direction (Fig. 22). Each toothed segment 8 is provided on its upper end (as shown in Fig. 22) with an arcuate extension 8' (Figs. 20, 22), provided with two lateral noses 13, 14. The nose 14 of each toothed segment 8 co-operates with a counting tooth for tens, and the nose 13 co-operates with a release lever 17, 18. The counting teeth 15 (Fig. 22) for tens, which correspond in their shape to the chain links 6'' (Fig. 33), i. e., are likewise angular are in shape, are individually rotatable on the interior wall of the casing 4 and project through the medium of their teeth respectively through a small slot 4'' (Fig. 22), which is provided in the line of projection of the slot 4', intended for the corresponding toothed chain 6 immediately behind the said slot 4' in the shell of the casing 4. In the same or in a separate slot each of the release levers 17, 18 is rotatably mounted on a pin 16. The rear arm 17 of each releasing lever is normally kept in the position shown in Fig. 22 by a small compression spring 20. The front end of each of the lever arms 18 is provided with a nose 19 rounded in front which, on an anti-clockwise displacement of the corresponding toothed segment 8 can, after initially moving out under the pressure of the spring 20, engage the nose 13 of the extension 8' and so secure the toothed segment 8 in its displaced position. The nose 14 of the projection 8' now lies beneath the corresponding tens-operating tooth 15 and secures it in its operative position (see Fig. 22). If the lever 17 is depressed in the manner hereinafter explained, its nose 19 again liberates the nose 13 of the toothed segment extension 8' with the result that the disc 10 and the toothed segment 8 are returned into their position of rest by the curved spring 12, the tens-operating tooth 15 thus losing its support up to then afforded by the nose 14 and consequently becoming inoperative.

The value-printing wheels 23 (Figs. 18, 20 and 38) of the addition-printing mechanism are mounted in the printing mechanism drum 1, so as to be freely rotatable, on an axle 22 that is parallel to the axle 2 and extend so far through a transverse slot of the drum casing that, when the printing mechanism drum is rolled, a particular one of the figures of each value-printing wheel 23 is printed. Each value-printing wheel 23 is

rigidly connected with a toothed wheel 23' which is continually in engagement with a toothed wheel 24'. The toothed wheels 24' are freely rotatable on an axle 24 parallel to the axle 22 and are driven by the toothed control chains 6 in so far as they are secured in their operative position by their cam discs 7 (Fig. 31). By means of the toothed wheels 23' the rotation imparted to the toothed wheels 24' is then transmitted to the value-wheels 23.

5
10

The value-printing mechanism or mechanisms

The value-printing mechanism (Figs. 27, 28 and 38) is mounted in a U-shaped frame 26, the cross-piece of which is secured on the inside of the drum end A (Fig. 18). In its two legs 27 and 28 there rests an axle 29 (Figs. 18 and 27) which at a suitable distance crosses the drum axle 2 and serves for rotatably mounting the value-printing wheels 30, 30', 30'', and 30''' of the value-printing mechanism. Each of these value-printing wheels is rigidly connected with a locking wheel 31 (Fig. 29), which co-operates with a spring-controlled locking catch 143, 144, 145 or 146, for the purpose of preventing accidental changes of position of the value-printing wheels. The two inner figure-printing wheels 30' and 30'' (Fig. 27) are each fixed on a short hollow shaft 32, 32', respectively, which shafts are pushed on the axle 22, each carry on their outer end a bevel wheel 34 and 35 respectively, and serve as a pivot for the neighbouring value printing wheel 30 and 30''' respectively, as well as for a toothed wheel 36 and 37 rigidly connected with the figure-printing wheels 30 and 30''', respectively. By means of its bevel or toothed wheel 34, 36, 37 or 35, each of the value-printing wheels 30, 30', 30'', 30''', can be adjusted independently of one another. The driving of the bevel or toothed wheels 34, 36, 37 and 35 is effected in the following manner:—

On a lateral extension 38 of both frame legs 27 and 28 there are fixed respectively angle pieces 40 and 40' (Figs. 18, 28 and 30) in such a manner that between each angle piece and the corresponding extension 38 a small interspace remains in which there is rotatably mounted on a third axle 42 and 43 a double bevel wheel 44, 44' and 45, 45' consisting of two bevel wheels rigidly connected with each other. The bevel wheel 44 of the double bevel wheel 44, 44' engages with the bevel wheel 34 of the value-printing wheel 30', whilst the bevel wheel 45 of the double bevel wheel 45, 45' engages with the bevel wheel 35 of the value-printing wheel 30''. With the toothed wheels 36, 37 of the two outer value-printing wheels 30 and 30''' there engage toothed wheels 47 and 48 respectively which are rotatable on short pins 46 and 46' (Fig. 28) of the frame legs 27 and 28, respectively, and are rigidly connected with bevel wheels 47' or 48', respectively. In the lower portion of the frame 26, 27, 28 there is mounted an axle 142 (Fig. 28) which is parallel to the axle 29, and on which the locking catches 143, 144, 145 and 146 for the locking wheels 31 of the value-printing wheels 30, 30', 30'' and 30''' are rotatable. Each locking catch is normally pressed by means of a compression spring 147, 148, 149 and 150 respectively into one of the notches 31' of the corresponding locking wheel 31, and is provided with an extension 152, 153, 154 and 155 respectively, the object of which will be hereinafter explained.

The upper ends of the frame arm 27, 28 are connected together by means of a bridge 49 (Figs. 18, 27 and 28), which is curved parallel to

40
45
50
55
60
65
70
75

the wall of the casing of the printing mechanism drum, and in which four shafts 51, 52, 53 and 54 (Fig. 38) are mounted. Each of these shafts carries a bevel wheel 55, 56, 57 or 58, which engages respectively with the above mentioned bevel wheels 44', 47', 48' and 45' (Figs. 27, 28, 18 and 31). The lower ends of the two outer shafts 51 and 54 rest in the right rectangularly bent portions 41, 41' of the angle pieces 40, 40' and the lower ends of the inner shafts 52 and 53 rest in a U-shaped support fixed between the legs 27 and 28. Each of the shafts 51 to 54 carries on its left-hand end (according to Fig. 18) which projects through the bridge 49 and an opening in the drum lid B, a toothed wheel 61, 62, 63 and 64 which lies in another plane than that of the remaining three toothed wheels. On the outer ends of the shafts 51 to 54 which project over the bridge 49, there is pushed a hollow shaft 65, 66, 67 and 68, on which a locking lever 69, 70, 71 and 72 is rigidly fixed. Each locking lever 69 to 72 is acted upon by a torsion spring 73, 74, 75 and 76, each of which is pushed on one of the hollow shafts 65 to 68 and one end of which rests against the corresponding locking lever and the other end on the edge or rods of a U-shaped bearing frame 77 which, as shown in Figs. 38 and 33 bridges the opening of the drum lid B (Fig. 18) and serves for mounting the outer ends of the shafts 51 to 54 (Figs. 27, 28 and 38). Owing to the pressure of the torsion springs 73 to 76 each of the locking levers 69 to 72 engages in one of the toothed wheels 61 to 64 and thus prevents an accidental change of position of these toothed wheels and consequently also of the value-printing wheels 30, 30', 30'' and 30'''', which are indirectly connected with the former through the shafts 51 to 54 as well as the toothed gearings 55, 44', 44 and 34, and 56', 47', 47 and 36, and 57, 48', 48 and 37, 40 and 58, 45', 45 and 35 respectively.

The value-setting device of the example according to Figs. 18 to 23

The setting of the value-printing wheels 30, 30', 30'' and 30''' is effected by means of the above described gear by toothed segments 79, 80, 81 and 82 (Figs. 18, 25 and 34) which can be brought into engagement respectively with the toothed wheels 61 to 64 and are respectively mounted on hollow shafts 83, 84, 85 and 86. The hollow shafts 83 to 86 have different lengths and are pushed on the drum axle 2 in a telescopic manner. On their right-hand end (according to Fig. 18) each of these hollow shafts is provided with a narrow longitudinal slot 88 (Figs. 32 and 34) and these slots are engaged by extensions 21 provided respectively on the hollow shafts 11, 11', 11'', 11''' (Figs. 20 and 32). The hollow shafts 83 to 86 (Figs. 18 and 24) are in this manner continually coupled with the hollow shafts 11, 11', 11'' and 11''' respectively. In the plate-shaped hub of each of the toothed segments 79 to 82 there is provided an arc-shaped slot 91, 92 (Fig. 32), which extends to 90° on both sides of the slot 88, thus through 180° and through which in this way the extensions 21 of the outer hollow shafts 11, 11', and 11'' engage in the corresponding hollow shafts 86, 85 and 84 (Figs. 18, 24 and 25). In this way there is afforded the possibility of rotating the four pairs of hollow shafts 83, 11'', and 84, 11', and 85, 11', and 86, 11, independently of each other for the purpose of setting the value-printing wheels 30, 30', 30'' and 30''''. Their rotation is effected with the aid of 75 setting discs 95, 96, 97 and 98 (Figs. 18, 23 and

35), or setting levers 118, 119, 120 and 121 (Fig. 24) which are fixed to the outer ends of the hollow shafts 83 to 86.

When setting discs are employed they are provided respectively with sector-shaped projections 99, 100, 101 and 102 (Figs. 18 and 23), which carry on their upper ends the numbers "0" to "9" respectively. All four extensions are covered by a hood 111, which is fixed to the left casing wall C of the roller stamp, and which by means of a narrow transverse slot 111' (Fig. 35) enables each of the numbers of the setting discs 95 to 98 to be read off, and its exact setting effected. On their rear sides the setting discs 95 to 98 are provided with toothed segments 103, 104, 105 and 106 respectively (Fig. 18) which normally engage in corresponding toothed segments 107, 108, 109 and 110 of the hub 111, and thus prevent accidental shifting of the discs 95 to 98, and consequently of the value-printing wheels 30, 30', 30'' and 30''''. A compression spring 112, which rests on one side against the disc 86 of a bearing ring D, fixed in the casing wheel C, and on the other side against the hub of the foremost toothed segments 82, and thus at the same time also against the hubs of the three rear toothed segments 81, 80 and 79, tends normally to secure the toothed segments 79 to 82, and consequently also the setting discs 98, 99, or 97, 100, or 96, 101, or 95, 102, rigidly connected with these toothed segments by the hollow shafts 83 to 86, in the position shown in Fig. 18. Should a shifting of the setting discs be required, the particular one of the four discs desired, for example, the disc 98, is pulled forward, i. e., to the left in relation to Fig. 18. In consequence of the rigid connection of the disc 98 with the toothed segment 79 lying close in front of the drum lid B, the toothed segment 79 also takes part in the movement to the left of the disc 98 so overcoming the resistance exerted by the spring 112, and carries with it the remaining three toothed segments 80, 81 and 82 as well as their hollow shafts 84, 85 and 86 and setting discs 97, 96 and 95—i. e., all the setting discs together with their corresponding hollow shafts 83 to 95, toothed segments 79 to 82, and extensions 99 to 102, will execute the movement to the left, when the engagement of the toothed segments 107 to 110 will be released. The same would take place if the setting disc 95 were to be pulled forward because, as shown in Fig. 18, this disc acts with its hub 95', on a hub of the setting disc 96 and further indirectly also on the hubs of the discs 97 and 98, and consequently pushes the three remaining setting discs in front of itself. If, finally, one of the setting discs 96 and 97 is pulled to the left (Fig. 18) the discs lying in front of it are taken with thereby directly, whilst the discs lying to the rear thereof are taken with thereby through the medium of the corresponding toothed segments 81 and 80. In all cases the lateral displacement of one of the setting discs 95 to 98 will result in a lateral displacement at the same time of the three others. In order to secure the setting discs in their displaced positions for the duration of their shifting, there is pushed on a hub 95' of the rearmost setting disc 95 a locking bar 115 (Fig. 37) which is provided with a suitable opening and is displaceable on its upper end by means of a slot on a pin 114 of the casing wheel C, and which is kept away from the inner surface of the hub 111 by means of a two-legged spring 117 fixed to a pin 113. The spring 117 tends continually to press the locking bar downwards; this, however, is pre- 75

vented as long as the setting discs are in their position of rest (Fig. 18) owing to the fact that the annular portion of the bar and a semi-circular rib 116 fixed thereto rest on the hub 95' of the setting disc 95. If, however, the setting discs 95 to 98 are moved in the manner described towards the left, the hub 95' liberates the locking bar 115, which has hitherto been secured in the position of rest, so that the locking bar 115 is now 10 pressed downward by the spring 117, and moves together with the rib 116 into the interspace between the hub 95' and the bar ring D. In this way, the turning into the position of rest of the setting discs that have been moved towards the 15 left is prevented until the locking bar 115, after the apparatus has been set, is pressed back into its initial position by hand, whereupon the setting discs are returned by the pressure of the spring 112 into their position of rest. The locking bar 115 is again secured in its original position by the hub 95' of the setting disc 95.

The value-setting apparatus of the example according to Figs. 24 and 25

25 In the case of the example according to Figs. 24 and 25 there are provided instead of the setting discs, four setting levers 118, 119, 120 and 121, which for the sake of more convenient manipulation are advantageously fitted on their ends 25 with handles 118', 119', 120' and 121'. They may, for example, be connected with the hollow shafts 30 83 to 86 by providing their hubs 122, 123, 124 and 125 each with an opening in the form of a regular polygon and sticking them on the suitably moved front ends of the hollow shafts. The levers 118 to 121 are covered by the round hood 130 which is fixed to the casing wall C and the diameter of which is such that the handles 118' and 121' of two of the levers protrude through slots of 35 their casing whilst the two other shorter levers 119 and 120 lie within the hood 130 but, however, with their nose-shaped handles 119' and 120' each protruding through an arc-shaped slot 131 in the front face. The outer edge of each slot 40 131 has a scale 132 with the numbers "0" to "9" thereon and serving for setting two of the setting levers—e. g., the cent units lever 118 and the cent tens lever 119. Each setting lever is provided on the rear side with a pin 134 which normally rests in one of the notches of a notched segment 137 or 138 fixed to the hood 130 or to the casing wall C and this prevents an accidental shifting of the setting lever. Should this take place, all the levers 118 to 121 must be moved 45 together towards the left (Fig. 24) and their pins 134 thus lifted out of the particular notches 137, 138 occupied by them. In addition there is arranged on the bearing ring D, fixed in the casing wall C, a cam 139 with which there can co-operate a lever arm 140 the hub 141 of which is freely rotatable on the outer hollow shaft 86. If the lever arm 140 is moved laterally out of its position of rest (Fig. 24) it slides on to the cam 139, moves in this way towards the left (Fig. 24) through 50 the height of the cam and in doing this presses all the setting levers outwards to such an extent that their pins 134 are lifted out of the notched segments 137, 138. The shifting of the lever can now be proceeded with and is then, by moving 55 back the lever arm 140 again secured in its position of rest, since the compression spring 112 immediately again returns the setting levers 118 to 121 with their corresponding hollow shafts 83 to 86 and toothed segments 79 to 82 into the position shown in Fig. 24. In order to be able 60

to read off at any time the position of the levers 118 to 121, there are provided on their hubs sector-shaped extensions which correspond to the extensions 99 to 101 (Figs. 23 and 35) of the setting discs 95—98 and like them are visible through 65 a slot 111 in the hood 130.

The method of use and operation of the value-setting apparatus

The apparatus is manipulated in the following manner:—

With the aid of the locking bar 115 (Fig. 37) or of the lever arm 140 (Figs. 25 and 24), first the notch lock of the setting discs 95 to 98 (Fig. 18) or of the setting levers 118 to 121 (Fig. 24) is unlocked and at the same time the toothed segments 79 to 82 (Figs. 18, 27 and 25) is brought into engagement respectively with the corresponding toothed wheels 61 to 64 (Figs. 25, 28, 18 and 24) since the setting segments, as stated above, take part in the common displacement of the setting discs or setting levers and in doing so are moved into the planes of the last mentioned toothed wheels. If now one or more of the setting members 95, 96, or 118, 119 for the cent units and cent tens is or are set to the desired value, this setting is transmitted by the toothed wheel 63 (Fig. 28), the shaft 52, the bevel wheels 56, 47' and the toothed wheels 47, 36 to the cent units printing wheel 30 or, by the toothed wheel 64, 30 the shaft 51, the bevel wheels 55, 44', 44, 34 and hollow shaft 33 (Fig. 27) to the cent tens printing wheel 30'. Excessive turning of the value-printing wheels is prevented in this case by the spring-controlled locking catches 71, 72 (Figs. 27 and 28) and 146, 145 which snap into the gaps between the teeth of the toothed wheels 64, 63 or 35 31 (Fig. 29). In order that the value-printing wheels should be adapted always to be shifted only when the printing mechanism drum 1 is in its 40 initial position, the already mentioned extensions 152 to 155 (Figs. 21 and 28) of the locking catches 143 to 146 co-operate in such a manner with the edge of the toothed chain casing 4 or with an opening 156 provided in the latter that the 45 locking catches lie in the path of the opening 156 only when the printing mechanism drum is in its initial position and consequently have sufficient play for being moved out whilst, after the rotation of the printing mechanism drum has begun, 50 they are kept by the edge of the toothed chain casing 4 in the position shown in Fig. 21 and consequently in engagement with the locking wheels 31, thus making rotation of the value-printing wheels 30, 30', 30'' and 30''' impossible. 55 The setting of the value-printing wheels can at any time be ascertained with the aid of the figures of the sector-shaped extensions 99 to 102 (Figs. 23 and 35) provided on the setting members 95 to 98 (Fig. 18) or 118 to 121 (Fig. 24), 60 that are visible through the slot 111' (Fig. 35) in the hood.

In consequence of the coupling of the hollow shafts 95 to 98 (Figs. 18 and 24) with the hollow shafts 11, 11', 11'' and 11''' effected by the extensions 21 (Figs. 20, 32 and 34) and the openings 88, the hollow shafts 11, 11', 11'' and 11''' and the cam discs 7 (Figs. 41 and 20) fixed thereon also take part in the rotation of the setting members 95 to 98 (Fig. 18) or 118 to 121 (Fig. 24). 65 According to the angle through which the particular setting member is turned, the corresponding cam disc 7 will with its raised edge step pass beneath a larger or smaller number of chain members 6'' (Fig. 33), pass the teeth of these 70 75

chain members outwards through the slot 4' (Fig. 18) and lock them in their operative position. The gear ratio of the toothed wheels 24' (Figs. 38 and 18), cooperating with the chain teeth 6' (Figs. 31 and 33) locked at the time being, to the toothed wheels 23' of the value-printing wheels 23 of the addition printing mechanism is in this case so chosen that, by means of one of the chain teeth located in the operative position, the corresponding value-printing wheel 23 will be moved on by a number unit. Thus, if for example, the value-printing wheel 30 of the value-printing mechanism has been set to the number "6" by means of the cent units setting number, 10 and accordingly the first six teeth of the cent units operating chain 6 have been locked in the operative position by the corresponding cam disc 7 (Figs. 31 and 20) the cent units printing wheel 23 of the addition printing mechanism is moved 15 through six units on each rotation of the printing mechanism drum 1. In a similar manner each further movement of the remaining addition-printing wheels 23 takes place in correspondence with the setting of the setting members 95 to 98 (Fig. 18) or 118 to 121 (Fig. 24). The values represented by the individual stamping operations are thus continuously summed up 20 in the addition printing mechanism 23 which prints the particular total reached by each stamping operation. The individual stamping operations produce in this case the impression represented in Fig. 19 on which, in addition to the value stamp proper 157 there appear a statement, as to the firm, an advertising matter or 25 cancellation 158, the apparatus number 159 and the impression 160 made by the addition printing mechanism 23. As may be seen from Fig. 19, the impression 157 by the value-printing mechanism lies horizontally and not vertically as in the previously described example, in the simultaneously 30 printed frame, so that it can be easily read off at a single glance. The addition of the impression of the total 160 to the stamp picture affords the advantage that the user of the apparatus can 35 at any time ascertain to what extent the amount prepaid by him has been exhausted. The printing of the frame enclosing the value figure 157 (Fig. 7), the statement as to firm, advertising matter or cancellation 158, of the apparatus number 159 and of any other matter is effected by 40 means of frame or plate-shaped printing blocks each of which is exchangeable.

The tens transmission to the printing wheel of the next higher order that takes place after each 45 passage from "0" to "9" of one of the value-printing wheels 23 (Figs. 18, 20 and 38) of the addition printing mechanism, is effected as follows:—

As soon as a change from "9" to "0" takes 50 place in the series of the figures to be printed by the printing wheels 23, one nose 25 provided on the corresponding printing wheel 23 is carried into the path of the corresponding toothed segment 8 (Figs. 18, 20 and 22) and takes the 55 latter with it to such an extent that the nose 13 of the extens' on 8' provided on this toothed segment first displaces the nose 19 of the neighbouring releasing lever 17, 18, whereupon the nose 19 snaps over and engages the nose 13 and 60 locks the toothed segment in the position shown in Fig. 22. The nose 14 of the toothed segment extens' on 8' then secures the tens operating tooth 15 in the operative position; the latter will 65 consequently, after the operating chain 6 lying 70 in a straight line therewith has moved on the

toothed wheel 24' and consequently the toothed wheel 23' and the printing wheel 23' of the next higher order through the set number of units, at once turn the latter printing wheel through a further unit by means of the toothed wheels 24', 23'. The "ten" of the value-printing wheel of the lower order that is assigned to the value-printing wheel of the next higher order is thus duly transmitted thereto. During the further rotation of the drum, the toothed wheel 24' finally moves over the outer arm 17 (raised by the spring 20) of the releasing lever 17, 18, depresses it and thus brings about the liberation of the toothed segment 8 which is immediately again returned into its position of rest by the curved spring 12. The tens-moving tooth 15 which has up to then been locked in its operative position is consequently again unlocked and the arrangement is ready for the next tens operation.

In order to characterize the impressions printed by the printing drum 1 according to the time, place and nature of the stamping operation, there may be provided instead of the printing plate intended for the impression 158 (Fig. 19) a special printing device the details of which may be seen in Figs. 38 and 39. It consists of a number of printing wheels 162 and 162' which are so mounted on two axles 161 and 161' within a frame 165 fixed between the printing mechanism drum walls A, B, that, like the value-printing 30 wheels 30, 30', 30'' and 30'''', they protrude through a slot in the drum casing. These printing wheels 162 and 162' each carry on their peripheries numbers, letters, pictures or the like and are rigidly connected respectively with locking wheels 163 and 163' each of which co-operates with a locking member 164 fixed to a cross-piece 166 of the frame in such a manner as to render impossible any accidental shifting of the printing wheels 162 and 162'.

The setting device for the value-printing mechanism of the example according to Figs. 1-5, 40 and 41

In the case of the stamping apparatus for printing only two-place values as shown in Figs. 1 to 5, 40 and 41, the setting device for the value-printing wheels is considerably simplified. The toothed segments, which are rigidly connected with the setting levers o1 and o2 and which correspond to the units and tens toothed segments 82, 81 of the example according to Figs. 18 to 25, engage in two toothed wheels 167 and 168, the units toothed wheel 167 of which is fixed on a solid shaft 169 whereas the tens wheel 168 is fixed to a hollow shaft 170 pushed on the shaft 169. The upper end of the shaft 169 is mounted in the bridge 171 and its lower end in an angle piece 172. On their lower ends the shafts 169 and 170 carry bevel wheels 173 and 174 respectively which engage respectively with bevel wheels 173' and 174'. The latter are, in turn, rigidly connected with toothed wheels 175 and 176 respectively, which by means of a second pair of toothed wheels 175', 176' drive the corresponding value-printing wheels 177 and 178. A frame 179, which is fixed between the two ends of the printing mechanism, drum, serves for mounting these value-printing wheels 177 and 178 and the corresponding locking parts not shown in Fig. 41.

The tens transmission of the printing adding mechanism and the device for locking the latter against accidental or fraudulent operation.

The tens transmission of the printing adding

mechanism and the device for locking the latter against accidental or fraudulent operation will now for the sake of simplicity be described with reference to the value stamping machine (shown in Figs. 1 to 5) for printing one or two place values.

In this machine the printing mechanism drum *g*, the units wheel 180a and the tens wheel 180b are driven by the value printing wheel 180 each through the medium of an operating wheel 181 through a toothed chain 182a, 182b, which comprises nine teeth and which is arranged in the manner hereinbefore described in an operating drum 183 and brings the particular number of teeth that are necessary into the operative position in accordance with the setting of the corresponding hollow shafts 184a, 184b. The tens chains 182a, 182b lie in the plane of the corresponding operating wheel 181 which is in constant engagement with the toothed wheel 185 of the corresponding value-printing wheel 180a or 180b. In order to prevent an accidental or fraudulent rotation of the printing adding mechanism 180, there co-operates with each of the two operating wheels 181 an approximately V-shaped locking lever 186 which is rotatable on an axle 187, is acted upon by a torsion spring 188 and secures the operating wheel 181 against rotation to the right as well as against rotation to the left. The lower arm 186a of this locking lever, which is shown in plan in Fig. 46, is bent bayonet wise, so that it can move upwards and downwards on the outer-side face of the operating wheel 181. The teeth of the toothed chains 182a, 182b are so wide that they can co-operate not only with the corresponding operating wheel 181, but also with the lower lever arm 186a of the locking lever 186 provided for the operating wheel 181. If no tooth of a toothed chain is in the operative position, the locking lever 186 maintains its locking position and so prevents a shifting of the corresponding value-printing wheel. If, on the contrary, a greater or smaller number of teeth have been pressed into the operative position, the lower arm 186a of the locking lever 186 moves, before the teeth in the operative position come into engagement with the wheel 181, first on to the teeth and is then lifted by them from the operating wheel 181b, so that the latter and consequently also the value-printing wheel 180a or 180b can now be moved on by the teeth by the amount to which the value-printing mechanism is set. As soon as the operating wheel 181 has passed the last tooth, the locking lever 186 returns into its position of rest shown in Fig. 42, in which it again locks the operating wheel 181 and the value-printing disc 180 or 180b integrally connected with the operating wheel 181.

In order to prevent a so-called "over-stepping" on setting the value-printing wheels 180a, 180b, there co-operates with the toothed wheel 185 of each of the two value-printing wheels 180a, 180b an approximately Y-shaped locking lever 189, which under the pressure of a spring 190 normally engages with its upper arm in the toothed wheel 185 and thus yieldingly secures the value-printing wheel in the position occupied thereby at the time being. The lower arm 189a of the locking lever 189, the front view of which is shown in Fig. 47, is bent bayonet-wise out of the plane of the toothed wheel 185 so that it lies in the plane of a locking wheel 191 fixed on a toothed wheel 185. As soon as for the purpose of moving the value-printing wheel 180a or 180b further the corresponding locking lever 189 is raised, its lower arm 189a engages with its upwardly directed nose

in the locking wheel 191 so that the value-printing wheel can only be rotated continually by one tens division before it can be moved on to a further figure by the next tooth of the toothed chain 182a or 182b.

For the purpose of transmitting tens from the units value-printing wheel 180a to the tens value-printing wheel 180b, there is fixed on the inner side of the value-printing wheel 180a an operating cam 192 (Fig. 48) which co-operates with a spring-controlled bell-crank lever 193 as soon as the value-printing wheel 180a passes from "9" to "0". The bell-crank lever 193 at this point assumes the position shown in broken lines in Fig. 48 in which it is immediately secured by a small spring-controlled locking lever 194, which is rotatable on the axle 195 of the locking lever 186 and, when the bell-crank lever 193 moves outwards, places its nose 196 over the pin 197 of this bell-crank lever.

Between the two toothed chains 182a, 182b, there is mounted in a slot in the operating drum 183 a two-armed lever 198, which lies in the plane of the bell-crank lever 193 and is normally kept in the position shown in Fig. 42 by a small compression spring. A laterally bent off nose 198a of this lever is of such a length that it reaches to the plane of the tens-operating chain 182b. The nose 198b arranged at the other end of the lever normally protrudes somewhat above the periphery of the operating drum 183. If on the passage of the value-printing wheel 188a from "9" to "0" the bell-crank lever 193 is moved out and has become locked in this position by the lever 194, it slides on rotation of the printing mechanism drum *g* over the nose 198b and in doing this moves a lever 198 outwards so that now its nose 198a is moved into the operative position. Since as already mentioned the nose 198a reaches to the plane of the tens operating toothed chain 182b and consequently also of the corresponding operating wheel 181, the nose 198a, acting as tens-operating tooth will, after the completion of the operation of the operating wheel 181, move the corresponding operating wheel through a further division and so perform the proper tens operation. On the further rotation of the printing mechanism drum, the locking lever 194 slides with its free end 199 over a pin 200 of the operating drum 183, and in doing this is moved out of its locking position and consequently again liberates the bell-crank lever 183 which is again returned to its position of rest by its spring.

In the appended claims the term "prepayment key" means a key for setting the value-stamping machine itself so that it becomes locked against further operation as soon as it has stamped amounts totalling to the prepaid amount to which the key is set and the term "prepayment" means the total of the amounts thus allowed to be stamped by the machine when so set by the key.

Having now particularly described and ascertained the nature of my said invention and in what manner the same is to be performed, I declare that what I claim is:—

1. A value-stamping machine with a removable registering prepayment key, comprising a main adding mechanism in said machine adapted to be operated only additively so as to be set to the actual cash value of the prepayment, and an adding mechanism in said key adapted to be set to the actual cash value of the prepayment at the same time as the main adding mechanism.

2. A value-stamping machine with a removable registering prepayment key, comprising a main

adding mechanism in said machine adapted to be set to the actual cash value of the prepayment, an adding mechanism in said key adapted to be set to the actual cash value of the prepayment, a coupling member on said machine for coupling together said key with said main adding mechanism when said machine is being set to the prepaid amount, and a locking device adapted to be caused by said coupling member to lock said machine against further operation as soon as said machine has stamped up to the prepaid amount.

3. A value-stamping machine with a removable registering prepayment key according to claim 2, comprising a toothed gearing in said machine for actuating said main adding mechanism adapted to be coupled together with said coupling member and said prepayment key when said machine is being set to said prepaid amount, said toothed gearing being thus adapted to take part in the key movement and to remain at rest after the withdrawal of said key.

4. A value-stamping machine with a removable registering prepayment key, comprising both in said machine and in said key a main adding mechanism adapted to be set to the actual cash value of the prepayment, a printing mechanism drum with addition-printing mechanisms, a hollow shaft rotatable on the axle of said printing mechanism drum, a printing wheel of each of said addition-printing mechanisms being connected with said hollow shaft and said hollow shaft extending outwardly through the adjacent drum end, two five-toothed operating wheels displaced half a division in relation to each other and mounted on the free end of said hollow shaft, and a double operating wheel mounted on the supporting frame of said printing mechanism drum and consisting of two five-toothed wheels and adapted to co-operate with the aforesaid five-toothed wheels in such a manner that on each operation of the latter the double operating wheels is alternately moved forward through an equal unit by the teeth of one or the other first mentioned five-toothed operating wheels.

45 5. A value-stamping machine according to claim 4, comprising a locking catch adapted normally to lock said double operating wheel against rotation and to liberate it only at the instant of its operation.

50 6. A value-stamping machine with a removable registering prepayment key, comprising both in said machine and in said key a main adding mechanism adapted to be set to the actual cash value of the prepayment, a coupling member on said machine for coupling together said key with said main adding mechanism in said machine when said machine is being set to the prepaid amount and, in said machine, a printing mechanism drum with addition printing mechanism, a hollow shaft rotatable on the axle of said printing mechanism drum, a printing wheel of each of said addition-printing mechanisms being connected with said hollow shaft and said hollow shaft extending outwardly through the adjacent drum end, two five-toothed operating wheels displaced half a division in relation to each other and mounted on the free end of said hollow shaft, a double operating wheel mounted on the supporting frame of said printing mechanism drum and consisting of two five-toothed wheels and adapted to co-operate with the aforesaid five-toothed wheels in such a manner that on each operation of the latter the double operating wheel is alternately moved forward through an equal unit by the teeth of one or the other first men-

tioned five-toothed operating wheels, a notched disc normally coupled with said coupling member, and a bell-crank lever for enabling said double operating wheel to transmit its operating movements to said notched disc and thus to bring said coupling member step-by-step into its initial position.

7. A value-stamping machine with a removable registering prepayment key, comprising both in said machine and in said key a main adding mechanism adapted to be set to the actual cash value of the prepayment, and in said machine a printing mechanism drum with addition-printing mechanisms and an edge with recesses, a hollow shaft rotatable on the axle of said printing mechanism drum, a printing wheel of each of said addition-printing mechanisms being connected with said hollow shaft and said hollow shaft extending outwardly through the adjacent drum end, two five-toothed operating wheels displaced half a division in relation to each other and mounted on the free end of said hollow shaft, and a double operating wheel mounted on the supporting frame of said printing mechanism drum and consisting of two five-toothed wheels and adapted to co-operate with the aforesaid five-toothed wheels in such a manner that on each operation of the latter the double operating wheel is alternately moved forward through an equal unit by the teeth of one or the other first men-

8. A value-stamping machine according to claim 4 comprising a locking catch adapted normally to lock said double operating wheel against rotation and to liberate it only at the instant of its operation, a cam disc shaped edge on the printing mechanism drum, a running wheel on the end of the locking catch that is remote from said double operating wheel adapted to enable said locking catch to cooperate with said cam disc shaped edge in such a manner that, shortly before the double operating wheel is operated, said running wheel falls into an opening in said edge and thus permits said locking catch to occupy its liberating position.

9. In a value-stamping machine, a stamping device comprising a printing drum with adjustable types, an adding device in said drum, means for feeding said adding device according to the actual value stamped, a controlling device actuated by said adding device, a locking device controlled by said controlling device and adapted to lock the machine, a lock cooperating with said locking device, a removable registering prepayment key adapted to be inserted in said lock and to be actuated therein to temporarily disengage said locking device for a predetermined total stamping value corresponding to the prepaid amount, a registering device in said key, means to actuate said registering device in accordance with the actuation of the key, and a registering device in said stamping machine actuated by said lock.

10. In a value-stamping machine, a stamping device comprising a printing drum with adjustable types, an adding device in said drum, means for feeding said adding device according to the actual value stamped, a controlling device actuated by said adding device, a locking device controlled by said controlling device and adapted to lock the machine, a lock cooperating with said locking device, a removable registering prepayment key adapted to be inserted in said lock and to be actuated therein to temporarily disengage said locking device for a predetermined total stamping value corresponding to the prepaid

amount, a registering device in said key, means to actuate said registering device in accordance with the actuation of the key, a registering device in said stamping machine actuated by said lock, a main adding device in said stamping machine and means for progressively feeding said main adding device equal to the values stamped.

11. In a value-stamping machine, a stamping device comprising a printing drum with adjustable types, an adding device in said drum, means for feeding said adding device according to the actual value stamped, a controlling device actuated by said adding device, a locking device controlled by said controlling device and adapted to lock the machine, a lock cooperating with said locking device, a removable registering prepayment key adapted to be inserted in said lock and to be actuated therein to temporarily disengage said locking device for a predetermined total stamping value corresponding to the prepaid amount, a registering device in said key, means to actuate said registering device in accordance with the actuation of the key, a registering main adding device in said stamping machine being set by the said lock to indicate the total, and a registering device in said stamping machine actuated by said lock.

12. A value-stamping machine with a removable registering prepayment key, comprising a registering mechanism in said machine adapted to be set to the actual cash value of the prepayment and an adding mechanism in said key adapted to be set to the actual cash value of the prepayment at the time the registering mechanism is being set. 5

13. In a value-stamping machine a stamping device with adjustable types, an adding device, 10 means for feeding said adding device according to the actual value stamped, a controlling device actuated by said adding device, a locking device controlled by said controlling device and adapted to lock the machine, a lock cooperating with said locking device, a removable registering prepayment key adapted to be inserted in said lock and to be actuated in it to temporarily disengage said locking device for a predetermined total stamping value corresponding to the prepaid amount, 15 a registering device in said key, means to actuate said registering device in accordance with the actuation of the key, and a registering device in said stamping machine actuated by said lock. 20
